(57) **CLAIM**

The ornamental design for an escutcheon, as shown and described.

DESCRIPTION

FIG. 1 is a perspective view of an escutcheon showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, with the left side elevational view being a mirror image thereof.

The broken line showing in FIGS. 1 and 2 is for illustrative purposes only and forms no part of the claimed design.
